United States Patent Office

Des. 184,934
Patented Apr. 21, 1959

184,934

BICYCLE PEDAL OR THE LIKE

Carl W. Hedstrom, Gardner, Mass., assignor to Hedstrom
Union Company, Fitchburg, Mass.

Application October 3, 1957, Serial No. 47,953

Term of patent 7 years

(Cl. D90—14)

Fig. 1.

Fig. 2.

Fig. 3.

Fig. 1 is a top plan view of a bicycle pedal or the like embodying my new design, the bottom being substantially the same as the top shown;

Fig. 2 is a side elevational view thereof, the opposite side being substantially the same as the side shown; and

Fig. 3 is an end elevation thereof.

I claim:

The ornamental design for a bicycle pedal or the like, as shown and described.
